ALLIGATOR WRENCH

Filed Dec. 16, 1929

Fig. 8. *Jose Rubalcaba*

UNITED STATES PATENT OFFICE

JOSÉ RUBALCABA, OF LOS ANGELES, CALIFORNIA

ALLIGATOR WRENCH

Application filed December 16, 1929. Serial No. 414,354.

This invention relates to improvements in alligator wrenches and has for its object to provide a simple, efficient, and inexpensive device of this character.

Another object thereof is to provide a tool having a fixed and a movable jaw which are arranged to be adjusted in various gripping positions as may be found desirable or practicable.

In the drawings, wherein similar reference characters designate similar parts,

Figure 1 is a side elevation of my invention,

Figure 2 is a cross section taken therethrough,

Figure 3 is a side elevation, partly in section, of a slightly modified form of my invention,

Figure 4 is a top plan view of the fixed jaw,

Figure 5 is a bottom plan view of the wrench of Fig. 3,

Figure 6 is a front end elevation of my invention,

Figure 7 is a rear end elevation of the parts thereof,

Figure 8 is a side elevation of the movable jaw.

In the drawings, wherein the details of my invention appear, 10 designates a handle having a head 11 formed with an integral jaw 14 and having a slot 12 formed transversely therethrough one wall of which curves as at 12c while the other wall is inclined as at 16e the slot 12 having a rearwardly extending counter bore therein. A movable jaw shank is provided and designated 16 and has a vertical slot 18 thru which projects a pin or set screw 21. Instead of a slot 18 a lateral groove shown in Figure 2 may be provided so that a set screw 21 may be tapped thru one of the parallel sides 12a, 12b of the head 11 as will be soon explained. The movable shank 16 has an integral jaw 17 thereon provided with teeth 17a and similar teeth 15 are formed on the fixed jaw.

The movable jaw 16 carries the pin or set screw 20 at its lower end designed to receive a cap 20b so that the movable jaw 16 may

be held against detachment from the head 11; the movable shank also has a lateral toe 19 designed to be shouldered against a counter bore in the shank 11.

In order to operate this alligator wrench 55 the set screw 21 may be loosened so as to disengage the movable jaw from the slot 12 in the fixed jaw as well as to adjust the same in position. It will also be seen that the slideable jaw shank 16 engages against 60 the curved edge 12c of the head 11 by shouldering the rear edges of this movable jaw shank against the inclined edge 16e and this will hold both the movable jaw 17 and fixed jaw 14 in their ultimate positions. 65

When the movable jaw is operated it is wedged against the inclined edge of the bolt and the bolt head 25 rubs against this inclined edge and locks all the parts together. I claim all variations falling within the 70 purview of the appended claim.

What I desire to claim is:

In a tool, in combination a handle carrying a fixed shank terminating in a forward curved serrated jaw, and having a central 75 vertical slot, said slot having a forward curved edge and a rearward inclined edge, a movable shank projecting slidably in said slot and rocking adjustably against said curved edge, a serrated curved jaw carried 80 at the forward end of the movable shank, the fixed shank and the movable shank having interengageable stops to shoulder the movable shank rigidly when its jaw engages work against the fixed jaw, means locking 85 the movable shank in adjusted position in said slot, and means carried by said movable shank and engageable with the fixed shank to prevent the accidental removal of the movable shank from the fixed shank. 90

In witness whereof he has hereunder set his hand this 4th day of December, 1929.

JOSÉ RUBALCABA.
